GASEOUS ELECTRIC DISCHARGE DEVICE

Hans Ewest, Berlin, and Georg Gaidies, Berlin-Pankow, Germany, assignors to General Electric Company, a corporation of New York

Application September 29, 1930, Serial No. 485,059
In Germany November 29, 1929

10 Claims. (Cl. 176—122)

The present invention relates to gaseous electric discharge devices generally and more particularly the invention relates to such devices of the positive column type in which the gaseous electric discharge passes through a constricted passage in the interior of the container of the device.

The object of this invention is to provide a gaseous electric discharge device to produce a point-like light source of great brilliancy and intensity, useful in the arts generally and being particularly useful in connection with television and spectrometry.

In accordance with its object the invention comprises a metal cylinder closed at each end to form a chamber in the interior of the glass container of the device. A filamentary incandescent electrode is arranged in said chamber, said electrode being the cathode. The anode is placed outside said chamber and in close proximity to the mouth 20 of a small diameter tube in the walls of said chamber, the open end of said tube being above the filamentary electron emitting cathode. The greater part of the discharge path is covered by the metal chamber and it extends from the cathode through the constricted tube to the anode. Thus the only freely visible part of the gaseous discharge is between the mouth of the tube and the anode. That part of the discharge concentrated in the tube of small diameter is the luminous positive column and is visible only in the direction of the tube and is an extremely small, brilliant and intense light source useful in the arts generally.

In the drawing accompanying and forming part 35 of this specification an embodiment of the invention is shown, in which

Fig. 1 is a side elevational view of the invention, partly in section.

Fig. 2 is a front elevational view of the stem, 40 the chamber and the anode members of the invention.

Like numbers denote like parts in both views of the device.

Referring to Fig. 1 the invention comprises a 45 glass container 1 which is similar in size to the well known incandescent lamp bulb of common household sizes. Leads 4, 5, 6, 7 are sealed into stem 2 of container 1. Lead 4 is connected to support 8 of the metal cylinder 9, said cylinder 9 being closed at one end by metal cap 10 and at the other end by plate 11 made of insulation material to form a chamber enclosing filamentary electron emitting cathode 12. The support wires 13, 14 of said cathode 12 pass through glass rods 50 15, 16 extending from stem 2 through insulation

plate 11 and are connected to current leads 5, 6. In the walls of chamber 9, 10, 11 is a laterally protruding tube 17 of small diameter located above the cathode 12 and at the greatest possible distance from said cathode 12. The anode 18 is 5 located underneath the end of the tube 17 in the container 1, said anode 18 being a transverse wire (Fig. 2) attached to a metal support 19 which is sealed into stem 2 and connected to lead 7. Container 1 is filled with the usual discharge conducting gases such as rare gases, or mixtures of such gases with common gases or metal vapors.

In starting the device cathode 12 is first heated by connecting leads 5, 6 into the circuit. When cathode 12 is heated to an electron emitting temperature one of the leads 5, 6 is disconnected from the current source. The line voltage of the source is then applied to the cathode 12 through lead 5 or 6 and to chamber 9, 10, 11 through lead 4 connected to lead 7. An electric discharge is thus 20 established between the inner walls of chamber 9, 10, 11 and the cathode 12 to ionize the gas in said chamber 9, 10, 11. This ionization of the gas, as is well known in the art, is of extremely short duration after the extinguishment of electric discharge so that the operation of disconnecting lead 4 from lead 7, so as to establish the electric discharge between cathode 12 and anode 18, must take place quickly. When this operation has been completed the electric discharge path between 25 cathode 12 and anode 18 extends through tube 17 and dips downward to anode 18. That part of the discharge path passing through tube 17 is the 30 luminous positive column; its brilliant and intense light is due to its concentration in the narrow tube 17 and the high current density it is possible to use in connection with the electron emitting cathode 12. Though that part of the electric discharge path between the mouth of tube 17 and the anode 18 is freely visible the small point-like light source 35 in tube 17 is visible through the opening thereof only in the direction of the arrow in Fig. 1. As the incandescent cathode 12 is located below tube 17 none of its emitted light is visible through the opening.

The discharge, as desired, is of the glow or the arc type to suit the particular service for which the tube is to be used.

While this description and illustration disclose a particular embodiment of the device it will be 50 understood that various substitutions, modifications, and changes in the form and details of the device and in its use and operation may be made by those skilled in the art without departing from the broad spirit and scope of the invention, for 55

- example, the anode 17, the chamber 9, 10, 11 and the cathode 12 may be arranged in other positions with respect to each other in the container 1; further, a time switch or any other suitable switch 5 means may be used to cut out of the circuit the chamber 9, 10, 11, and the anode 18 is, when desired, made annular and of wire or tubing and arranged in concentric or parallel relation along the horizontal axis of said tube 17.
10. What we claim as new and desire to secure by Letters Patent of the United States, is:
1. The method of starting an electric discharge lamp, comprising a container, electrodes sealed therein, a gaseous filling therein, a metal chamber in said container, and a tube of small diameter in the walls of said metal chamber, one 15 of said electrodes being arranged in said chamber, another of said electrodes being arranged outside of said chamber and adjacent the exterior end of said tube, which consists in connecting said chamber into the circuit as an anode during the starting operation and disconnecting said chamber from the circuit during the normal operation of the lamp.
  2. In combination, an electric discharge lamp comprising a container, electrodes sealed therein, a gaseous filling therein, a metal chamber in said container, said metal chamber having a constricted portion along the discharge path between 20 said electrodes, one of said electrodes being mounted in said chamber, another of said electrodes being mounted outside of said chamber and adjacent said constricted portion and means to connect said chamber into the circuit as an electrode during the starting period and to disconnect said chamber from the circuit during 25 the normal operation of the lamp.
  3. An illuminating lamp comprising an envelope containing a heated electrode, an opaque chamber of conductive material within the envelope enclosing said electrode, and an electrode without the chamber, said chamber being provided with a restricted open nipple to permit the discharge to pass between the electrodes, and 30 said nipple being directed so as to project light axially thereof through said envelope.
  4. An illuminating lamp comprising a tube

containing a cathode, and a relatively long metallic passage through which the discharge is adapted to pass, a metallic discharge nozzle at the end of said passage and an anode adjacent and around said nozzle.

5

5. An illuminating lamp comprising an envelope, a metallic chamber therein provided with a metallic discharge nipple, a heated cathode in the chamber, and an anode beyond the nipple and provided with an opening in alignment therewith.

10

6. An illuminating lamp comprising an envelope containing gas under substantial pressure, a metallic chamber within the envelope provided with a metallic discharge nipple, a cathode within the chamber, and an anode beyond the nipple and provided with an opening in alignment therewith.

15

7. An illuminating lamp comprising an envelope, a metallic chamber therein provided with a metallic discharge nipple, a hot cathode ionizer within the chamber and an anode without the chamber said nipple being directed so as to project light axially thereof through said envelope.

20

8. An illuminating lamp comprising an envelope containing gas under substantial pressure, a metallic chamber provided with a discharge nipple directed so as to project light axially thereof through said envelope, a hot cathode ionizer within the chamber, and an anode without the chamber.

25

9. An illuminating lamp comprising an envelope, a metallic chamber therein provided with a metallic discharge nipple directed so as to project light axially thereof through said envelope, a cathode ionizer within the chamber, and an anode without the chamber.

30

10. An illuminating lamp comprising an envelope containing gas under substantial pressure, a chamber within the envelope provided with a discharge nipple, both formed of opaque electrically conductive material, a cathode within the chamber and an anode beyond the nipple and provided with an opening in alignment therewith.
